GAUGE FOR MEASURING WIND VELOCITY AND DIRECTION

Bo Gunnar Lonnstedt, Kvarnbergsvagen 23,
S-141 45 Huddinge, Sweden

Filed Dec. 26, 1973, Ser. No. 427,445

Claims priority, application Sweden June 26, 1973

Term of patent 14 years

Int. Cl. D10—04

U.S. Cl. D10—53

FIG. 1

FIG. 2

FIG. 3

FIG. 4

FIG. 1 is a bottom plan view of a gauge for measuring wind velocity and direction, showing my new design.

FIG. 2 is a side elevational view thereof;

FIG. 3 is an elevational view thereof from the side opposite FIG. 2; and

FIG. 4 is a top plan view thereof.

I claim:

The ornamental design for a gauge for measuring wind velocity and direction, as shown.
